CLAIM

The ornamental design for a hose connection fitting, as shown and described.

DESCRIPTION

FIG. 1 is a front, side, and top perspective view of a hose connection fitting showing the new design;

FIG. 2 is a front elevation view thereof;

FIG. 3 is a rear, side, and top perspective view thereof;

FIG. 4 is a rear elevation view thereof;

FIG. 5 is a top plan view thereof;

FIG. 6 is a right-side elevation view thereof;

FIG. 7 is a left-side elevation view thereof as compared to FIG. 6; and,

FIG. 8 is a bottom plan view thereof.

The broken lines and unshaded areas of the hose connection fitting depict portions of the hose connection fitting that form no part of the claim.
